CHEST OR SIMILAR ARTICLE OF FURNITURE

John O. Van Koert, New York, N. Y., assignor to Drexel Furniture Company, Drexel, N. C., a corporation of Delaware

Application August 2, 1955, Serial No. 37,261

Term of patent 14 years

(Cl. D33—6)

Fig. 1.

Fig. 2.

Figure 1 is a perspective view of a chest or similar article of furniture showing my new design; and Figure 2 is an end view thereof.

The central portion of the chest has been shown in dotted lines to indicate the chest may be of varying widths with conventional handle elements also shown in dotted lines. The back of the chest (not shown) is plain.

I claim:

The ornamental design for a chest or similar article of furniture, as shown and described.
